(57) **CLAIM**

The ornamental design for a pocket mirror, as shown and described.

DESCRIPTION

FIG. 1 is a perspective view of a pocket mirror according to the present invention with the light emitting diodes (LEDs) off;

FIG. 2 is a perspective view of the pocket mirror with the LEDs on;

FIG. 3 is a top view thereof;

FIG. 4 is a front view thereof;

FIG. 5 is a rear view thereof;

FIG. 6 is a bottom view thereof;

FIG. 7 is a left side view thereof; and,

FIG. 8 is a right side view thereof.

Each of the circular features shown in stippling illustrate a light emitting diode.

The features shown in broken lines illustrate environmental structure and form no part of the claimed design.
